UNITED STATES PATENT OFFICE.

FRANK ZALESKI, OF SOMERVILLE, MASSACHUSETTS, ASSIGNOR TO REECE SHOE MACHINERY COMPANY, OF BOSTON, MASSACHUSETTS, A CORPORATION OF MAINE.

METHOD OF MAKING COMPOSITE INSOLES.

1,211,520.

Specification of Letters Patent.

Patented Jan. 9, 1917.

Application filed October 21, 1916. Serial No. 127,012.

To all whom it may concern:

Be it known that I, FRANK ZALESKI, a subject of the Emperor of Germany, residing at Somerville, county of Middlesex, State of Massachusetts, have invented an improvement in Methods of Making Composite Insoles, of which the following description, in connection with the accompanying drawing, is a specification, like characters on the drawing representing like parts.

10 In a co-pending application Se. No. 121,875, filed September 23, 1916, by A. R. Schoenky, is illustrated a composite insole comprising an inner member having the edge portion thereof folded back onto the body thereof and an outer member having the edge portion projecting beyond the periphery of the inner member and formed by folding back on itself the portion of the outer member directly circumjacent the inner member, the peripheral edge of said outer member being free and forming a lip. In an insole of this type, the portion of the outer member which is folded back on itself and which is directly circumjacent the peripheral edge of the inner member constitutes the so-called feather edge of the insole, and in order that the insole may be practical, it is essential that the portion of the outer member which is thus folded back should be firmly secured to the body of the outer member. This may be done by cementing the folded portions together. In the commercial manufacture of insoles of this type, the folding of the outer member will be done by means of a folding machine, and the use of cement for cementing the folded portion of the outer member together is liable to interfere with the operation of the folding machine.

40 The object of my invention is to provide a novel method of making the insole by which the folded-over portion of the outer member of said insole can be caused to firmly adhere to the body thereof, thus producing a rigid and stiff feather edge on the insole without, however, interfering in any way with the normal operation of the folding machine by which the outer member is thus folded. I accomplish this by providing the 45 face of the outer member with a coating of adhesive which when cold and dry is not sticky or tacky, but which when heated will become sticky and adhesive. The folded inner member is placed on the face of the outer member which is thus prepared and

the projecting portion of the outer member is then folded over by means of a folding machine or otherwise to produce the folded edge of the insole, and the body and folded portion of the outer member are then subjected to heat which softens the adhesive sufficiently to cause the folded-over portion to adhere to the body thereof and said body to adhere to the inner member.

50 In order to give an understanding of my invention, I have illustrated in the drawings one way of practising my invention which will now be described, after which the novel features will be pointed out in the appended claims.

55 Figure 1 of the drawings is a perspective view showing an insole made in accordance with my invention; Fig. 2 is a similar view showing the inner member with its edge folded; Fig. 3 is a perspective view showing the blank from which the outer member is formed, which blank is provided with the coating of adhesive; Fig. 4 is a perspective sectional view showing the inner member placed in position on the outer member preparatory to folding the edge of the outer member; Figs. 5, 6 and 7 are views showing the steps of folding the projecting edge portion of the outer member.

60 Before describing my improved process, I will refer briefly to the complete insole. This comprises an outer member 1 and an inner member 2, each of which may be made of relatively-thin sheet material, such, for instance, as leather, fabric, or other suitable material. The inner member 2 has the edge thereof folded over onto the body, as shown at 3, and the outer member extends beyond the inner member, and the portion of the outer member immediately circumjacent the inner member is folded back on itself, as shown at 4, and the edge of the folded-back portion is then turned upwardly to present a lip 5. This folded portion 4 of the insole constitutes the feather edge thereof, and the 65 lip 5 together with the folded-over edge 3 of the inner member constitute the inseam-receiving rib for receiving the inseam stitches in the manufacture of the boot or shoe. The folded-over portion 4 of the outer member is firmly secured to the body of the outer member so as to make a stiff and solid feather edge to the insole.

70 In making this insole by my improved method, I first form the inner member from

a suitable blank by folding the edges 3 there over, as shown in Fig. 2. The outer member is made from a blank such as shown in Fig. 3 which is somewhat larger than the inner member. One face of this blank is provided with a coating 6 of adhesive material which when dry will adhere to the insole, but will not present a sticky or tacky surface. This coating should also be of such a nature that when it is heated it will soften and become sticky or tacky. While any suitable adhesive material having these characteristics may be used, I will preferably use an adhesive material, such as rubber cement. This may be provided in liquid form by dissolving or cutting the rubber in naphtha or benzine, and when it is applied to the surface of the blank 7 for the outer member, it will adhere thereto but will soon become sufficiently dry so that the coated surface of the blank 7 will not be sticky or tacky. The blanks in this condition can be readily handled without sticking together and as freely as they could be if there was no coating of adhesive material applied thereto. If, however, the blank is heated, the adhesive coating will soften sufficiently to become sticky. After the blank 7 for the outer member has thus been provided with the coating of adhesive and has become dry enough to be handled, the folded inner member 2 is placed on the outer member with the edge portion 8 of the outer member projecting, as shown in Fig. 4, and said projecting edge of the outer member is then folded back on itself, as shown at 4, and upwardly to present the upturned edge 5, as shown in Fig. 1. In thus folding the edge portion 8, it will be convenient to use a folding machine having the principal elements shown in Figs. 5, 6 and 7, although so far as the invention is concerned, the folding might be done by hand or in any suitable way. The elements of the folding machine illustrated comprise a table or work support 9 on which the outer member is placed, a holding member 10 adapted to rest on the inner member 2 of the insole and clamp the latter against the under member 1, collapsible forming or gage elements 11 in the form of sheets over which the edge 4 may be folded, and folding elements 12 constructed to engage the projecting edge 8 of the under member 1 and fold the latter over the formers 11 and then press the folded portions together. The former elements 11 are constructed to be movable laterally so that they can be withdrawn when the fold is completed. In making the fold 4, the outer member 1 is placed on the work support 9 with the edge 8 of the outer member projecting beyond the edge of the work support and overlying the folding elements 12. The inner member 2 with its edge folded is then placed in position on the under member 1 and the clamping member 10 is brought

against the member 2 to hold the latter in position. The former elements 11 will be expanded into the position shown in Fig. 5. The folder elements 12 are then moved upwardly into the dotted line position Fig. 5, 70 thus turning up the edge 8 around the former elements 11, and said folder elements are then moved inwardly over the former elements, as shown in Fig. 6, thereby folding the edge of the outer member over said former elements 11 and against the clamping member 10. The former elements are then withdrawn inwardly and the folder elements 12 are moved downwardly to set the fold 4, as seen in Fig. 7. The member 9 and the folder elements 12 are heated so that during the folding operation, the outer member will be sufficiently heated to soften the coating 6 of adhesive material and render it sticky or tacky. By the time that the fold 85 4 is made and pressed together, as shown in Fig. 7, the adhesive 6 is sufficiently softened so that when the folder elements 12 are pressing the fold 4, said fold will be caused to adhere to the body of the insole. The heat produced in the work support 9 also softens the adhesive on the body of the outer member 1 so that the inner and outer members will be caused to firmly adhere together. 90

In the operation of the folding machine, 95 it is essential that the former elements 11 should not stick or adhere to the coated surface of the under member 1 because if this occurs, a proper fold cannot be made as the withdrawing movement of the former elements 11 will disturb the fold. By using adhesive material such as above described, the former elements 11 can be moved freely without disturbing the fold in any way because the adhesive will not become sticky or 100 tacky until it has been heated after the fold has been made and while the fold is being set, as shown in Fig. 7.

I claim:

1. The process of making a composite insole comprising an inner and an outer member which consists in providing the outer member with a coating of adhesive material which is not sticky or tacky when dry but which becomes sticky or tacky when subjected to heat, folding the edge of the inner member back on itself, placing the folded inner member upon the coated face of the outer member, folding the projecting portion of said outer member back onto the body 110 thereof and forming its peripheral edge into a lip, and subjecting said outer member to the action of heat whereby the adhesive coating becomes sufficiently tacky to cause the two members to adhere together and to cause 115 the folded-over portion of the outer member to adhere to the body thereof. 120

2. The method of making a composite insole comprising an inner and an outer member which consists in applying to one face 130

of the outer member a coating of adhesive material which when dry will not be sticky or tacky but which will become sticky or tacky when subjected to the action of heat, 5 placing the inner member on the coated face of the outer member when the latter is dry, folding back directly on itself the portion of the projecting edge of the outer member immediately circumjacent the edge of the inner member thereby to make a fold in the 10 outer member which is situated entirely exterior to the inner member and subjecting the outer member to sufficient heat during the folding operation to soften the adhesive coating and render the same sticky or 15 tacky.

In testimony whereof, I have signed my name to this specification.

FRANK ZALESKI.
